UNITED STATES PATENT OFFICE.

IRA STRINGFELLOW, OF BROOKWOOD, ALABAMA, ASSIGNOR OF ONE-HALF TO WESLEY STRINGFELLOW, OF BROOKWOOD, ALABAMA.

TRAIN-PIPE-HOSE COUPLING.

1,243,778.

Specification of Letters Patent. Patented Oct. 23, 1917.

Application filed May 28, 1917. Serial No. 171,426.

To all whom it may concern:

Be it known that I, IRA STRINGFELLOW, a citizen of the United States of America, residing at Brookwood, in the county of Jefferson and State of Alabama, have invented certain new and useful Improvements in Train-Pipe-Hose Couplings, of which the following is a specification.

My invention relates to automatic couplings for train pipe air hose or other train pipe lines.

The automatic car coupler has made it unnecessary for men to go between cars to couple cars together but up to this time the general practice made it necessary for the train crew to work between the coupled cars in order to connect the air, steam and water hose connections and to open the valves in the train pipe lines. My object is to avoid this risk and hazard and to that end I have devised an apparatus which will act automatically to connect a train pipe line for air, steam or water and which is obviously capable of adaptation to couple one or more train pipe lines carrying such fluids.

One object of my invention is to so design the automatic couplings that they will have a maximum freedom of play both vertically and horizontally after they are coupled but will be held with rigidity and accuracy in the predetermined position requisite for effecting a coupling.

A further object is to adapt the couplings to automatically open and close the valves in the train pipe line so that the latter will be opened when the coupling is closed and closed when the coupling is opened.

My invention also includes the novel details of construction and arrangements of parts, which in their preferred embodiment only are illustrated in the accompanying drawings which form a part of this specification, and in which:—

Figure 1 shows a bottom plan view with two cars with the ordinary car couplings omitted and with the automatic hose couplings in coupled position.

Figs. 2 and 3 are similar views showing the hose couplings in open position ready to be coupled.

Fig. 4 is a detail front view of the guide and bracket in which the pivoted member of the coupling is guided, the coupling being shown in full and dotted lines in coupled and uncoupled positions.

Similar reference numerals refer to similar parts throughout the drawings.

I have illustrated my invention formally as applied to railway cars 1 and 2, each of these cars being provided with the ordinary type of bottom sills 3. Across these sills is bolted or made fast a plate 4 which overhangs at one end to form a bearing for a swinging bar 5 which projects forward beyond the adjacent end of the car and passes through a slot provided in the vertical member 6 of a bracket 7, which bracket is bolted to the underside of the sills, beams or other elements between which the draft rigging for the car coupler (not shown) is mounted. This bracket projects nearly to one side of the car and in this lateral projection is disposed the guide slot which receives the arm 5. This slot has a contracted neck near its end adjacent to the center of the car which merges at one end into a contracted seat 8 that snugly receives the bar 5 and at its other end merges into an enlarged and elongated slot 9 in which the bar 5 is free for substantial vertical and horizontal play. As will be seen in Fig. 4, the bar 5, when forced past the contracted neck of the slot into the seat 8, makes a fairly close fit therein and stands almost parallel with the sills 3. The object of the close fit provided is to bring the bar to a predetermined position when uncoupled, as shown in Figs. 2 and 3, whereas when the bar is coupled it works in the enlarged portion 9 of the slot and is there free to play vertically, as indicated by the dotted line 90 positions shown in Fig. 4. In order to normally draw the bar 5 into the position shown in Fig. 2, I provide a rod 10 carrying at one end a yoke 11 which embraces the bar 5 which is held in the yoke by a bolt 12 connecting the outer ends of the yoke arms, see Fig. 4. The yoke is so designed that the bar 5 is free to move angularly relatively thereto while the rod itself is confined to a straight line movement crosswise of the car by working in alining openings in the vertical webs 13 and 14 of the bracket 7. Between these webs the rod is provided with a washer 15 made fast thereon by a key or set screw and between this washer and the bracket 14 is interposed a coil spring 16 surrounding the rod 10 and acting against the washer to urge the rod in a direction to draw the bar 5 to the position shown in Fig. 2 and to resist with a very considerable pressure the out-

ward movement of the bar 5 which occurs while a coupling is being made. The springs 10 of opposing couplings thus act against each other being compressed by the approach of the cars 1 and 2 and will hold the couplings in interlocked relation with sufficient force to insure a pressure tight joint.

On the free end of each bar 5 I pivot an arm 17 carrying a coupling head 18. Each arm 17 is pivoted to its respective bar 5 at an intermediate point and has its rear end which extends beyond the pivot connected to a rod 19 which extends back under the rear end and is connected to a handle 20 of a rotary valve 21 in the train pipe line 22. A coiled spring 23 surrounds the pivot pin 24 which connects the bar 5 and arm 17 and its free ends are caused to engage said bar 20 and arm in such manner as to urge them apart and toward the relative position shown in Fig. 2. The power of this spring is sufficient to positively snap the valve 21 closed when the heads 18 are uncoupled.

Each coupling head 18 comprises a nipple 25 to which the air or other train pipe hose 26 is coupled at one end, the other end of the hose being connected to the train pipe line 22. This nipple connects with a passage 27 leading toward the front end of the coupling head and then turns at right angles to open through the front vertical face of the coupling. Here a rubber gasket 28 is provided surrounding the open end of the passage. In the rear of the gasket is a forwardly opening, flaring socket 29 for guiding and centering the tapered tip 30 of the opposing coupling head.

In operation, the coupling heads 18 are automatically drawn by the action of springs 16 to the position shown in Figs. 2 and 3, in which the bars 5 are held rigidly in the contracted seats 8 in the brackets and are therefore in position to present their respective heads 18 in position to engage each other as the cars approach, it being noted that the rods 19, co-acting with the valve handles 20, serve to limit the outward swing of the arms 17 responsive to the action of the springs 23. As the cars approach, the coupling heads 18 meet and engage and as they press together the taper tip 30 of each head will be received in the socket 29 of the opposing head. As the cars continue to approach the bars 5 are forced to swing outwardly in opposite directions against the action of the springs 16 until the couplings assume the position shown in Fig. 1, this action serving to put the springs 23 and 16 under tension and these springs serve to hold the coupling heads 18 positively engaged. When thus coupled, the bars 5 stand near the outer ends of the enlarged slots 9 in the brackets and are therefore free to have considerable vertical and horizontal

play back and forth as the cars move relatively in rounding curves and following track irregularities.

Having thus described my invention, what I claim as new and desire to secure by Letters Patent, is:—

1. An automatic train hose coupling comprising a coupling head having an air hose connection, an arm carrying the coupling head, a horizontally movable bar to the forward end of which said arm is connected and which bar is pivotally connected to the car at its rear end, guide means for the bar, and spring means to yieldingly resist the outward pressure of the car, due to the meeting of opposing coupling heads, substantially as described.

2. An automatic train hose coupling comprising a coupling head having an air hose connection, an arm carrying the coupling head, a horizontally movable bar to the forward end of which said arm is connected and which bar is pivotally connected to the car at its rear end, guide means for the bar, and spring means to yieldingly resist the outward pressure of the bar, due to the meeting of opposing coupling heads, said guide means having a contracted seat to receive and hold the bar in predetermined uncoupled position, substantially as described.

3. In a train pipe coupling, a horizontally swinging bar connected to the car and projecting beyond an end thereof, a vertical guide bracket having a guide slot in which said bar is horizontally movable, said slot having a contracted seat at the end nearest the center of the car, which seat is adapted to receive the bar with a snug fit, spring means to urge the bar into said seat, and a coupling head pivotally connected to the free end of the bar and having an air hose connection, substantially as described.

4. In a train hose coupling of the character described, a horizontally swinging support mounted on the car, guides for the support, spring means to resist the outward sidewise movement of the support, a train pipe line, a rotary valve therein having a handle, an arm, a coupling head mounted on said arm, a hose pipe connecting said head and pipe line, means to pivot the said arm at an intermediate point to said support, and a rod connecting the end of the arm near said pivot to the valve handle, as and for the purposes described.

5. A train pipe hose coupling comprising a horizontally swinging support mounted on the car, spring means to resist the outward movement of said support, an arm pivoted at an intermediate point to the outer end of the support, a spring acting between the support and arm to urge the latter away from the support, a rod connected to the rear end of the arm beyond its pivot point, a train pipe line, a rotary

valve therein connected to and adapted to be operated by the rod, and a hose connecting said pipe line to the coupling head, substantially as described.

- 5 6. In a train pipe hose coupling of the character described, a bracket mounted transversely under the end of the car and having a vertical member extending laterally and slotted, the slot having a contracted throat near the center line of the car, a bar pivoted to the car and adapted to swing horizontally in said slot, spring means urging said bar toward said throat, an arm pivoted to said bar, spring means to force the arm outwardly from the car, means to limit the outward swing of the arm on the bar, a coupling head carried on the free end of the arm, and a train hose pipe connected to the coupling, substantially as described.
- 10 15 20 25 30 35 40
7. In a train pipe hose coupling of the character described, a bracket mounted transversely under the end of the car and having a vertical member extending laterally and slotted, the slot having a contracted throat near the center line of the car, a bar pivoted to the car and adapted to swing horizontally in said slot, spring means urging said bar toward said throat, an arm pivoted to said bar, spring means to force the arm outwardly from the car, means to limit the outward swing of the arm on the bar, a coupling head carried on the free end of the arm, and a train hose pipe connected to the coupling, substantially as described.

transversely under the end of the car and having a vertical member extending laterally and slotted, the slot having a contracted throat near the center line of the car, a bar pivoted to the car and adapted to swing horizontally in said slot, spring means urging said bar toward said throat, an arm pivoted to said bar, spring means to force the arm outwardly from the car, means to limit the outward swing of the arm on the bar, a coupling head carried on the free end of the arm, and a train hose pipe connected to the coupling, substantially as described.

In testimony whereof I affix my signature.

IRA STRINGFELLOW.
